UNITED STATES PATENT OFFICE

HERMAN J. HAMMERLY, OF WALLINGFORD, CONNECTICUT, ASSIGNOR TO THE TRUMBULL ELECTRIC MANUFACTURING COMPANY, OF PLAINVILLE, CONNECTICUT, A CORPORATION OF CONNECTICUT

INCLOSED SAFETY SWITCH

Application filed October 19, 1928. Serial No. 313,550.

My invention relates particularly to that type of inclosed switches which employ replaceable fuses. The main object is to provide a simple but reliable interlocking mecha-

nism which will prevent access to the fuses when the switch is in the closed circuit or on position, but which will permit access to the fuses when the switch is in the off position without opening the main cover of the switch.

10 Another object is to provide an interlocking construction in which the parts will co-operate to automatically open the switch should an attempt be made to close the switch box cover while the shutter door is open and the switch is in closed circuit position and thus prevent a careless operator from leaving the cover closed with the switch in closed circuit position and the shutter door open and with the fuses exposed.

20 Another object is to provide an interlocking construction which will function under the conditions and in the manner specified in the preceding paragraph and in such a manner that the closing impact of the switch box cover will be cushioned by the resultant engagement and movement of the co-related parts.

Another object is to provide an interlocking construction of the forementioned character in which no injury to any of the co-related parts can be caused by the careless closing of the switch box cover when the parts are in a relatively incorrect position.

30 Another special object is to provide an interlocking mechanism of the character described in which some of the parts are carried by the switch box cover and some are mounted in the box proper.

40 For my present purpose the cover of the switch box is provided with an opening in register with the fuses and a shutter which normally closes this opening. Although the specific construction of the switch mechanism itself is not a part of my present invention,

45 nevertheless the invention contemplates an interlocking device which is simple and reliable and which co-acts particularly well with the type of switches in which the fuses are positioned above the switch blades, and

50 for use in connection with this type of

switches the present invention is an improvement over the construction of the Platt Patent 1,489,712, which broadly covers the present invention.

In my present invention, the interlocking member is in the form of a lever pivotally supported in the box at a point intermediate the ends of the lever. The inner end of the lever is provided with an open slot which engages the operating crank which extends back of the insulating base of the switch. A shoulder or hook portion at the outer end of the lever, stands in the path of movement of a part of the shutter or slide when the switch is closed, so as to prevent the opening movement of the shutter when the switch is in the closed circuit or on position.

The shutter and the latch lever are so constructed and co-related that, if the box cover is closed while the shutter is open and the switch is in the on position, the projection carried by the shutter will strike against the latch lever and automatically open the switch.

The co-relation of the switching parts, the latching lever and the shutter is such that the closing impact of the cover is cushioned and, further, there is no possibility of injury to any of the parts of the switch or the interlocking members by the careless closing movement of the cover, no matter what relative position the respective parts may occupy.

The switch operating and latching mechanism is so constructed that it may be assembled in the box and tested before the switch proper is installed, and because of its detachable connection with the operating crank the switch may be removed from the box without disturbing the operating or latching parts.

Fig. 1 is a perspective view of a construction embodying the improvements of my invention, the switch being shown in the closed circuit position and the cover being shown open and with the slide or shutter partly open.

Fig. 2 is a transverse section showing the switch in the open circuit position and the cover of the box closed.

Fig. 3 is a perspective view showing the box, parts being broken away to show the in-

terior with the switch operating and latching mechanism.

Fig. 4 is a longitudinal section showing the switch closed and the shutter latched so that it can not be opened.

Fig. 5 is a corresponding section showing the switch open and the shutter open.

Fig. 6 is a transverse section showing the parts of the switch in the closed circuit position and the action of the shutter against the latching lever when the cover is being closed.

The box 5 with its cover 6 hinged for instance at 7, may be of any suitable construction preferably of sheet steel. The box is preferably provided with a spring catch 8 adapted to project through a slot 9 in the cover when the cover is closed and adapted to facilitate sealing or locking the box to prevent access to the circuit terminals.

The switch itself is preferably provided with an insulating base 10, supported on brackets 11, which are suitably secured in the box. The particular switch illustrated, is intended for a three wire system. This, however, is immaterial to the present invention and it will therefore be necessary to describe only a single unit of the switch which includes two stationary contact jaws 12 and 13. The connecting blade 14 carried by an insulating bar 15 has a number of actuating connector rods 16 which extend through guide plate 17 and are detachably connected with the switch operating crank 18 back of the base. This crank is provided with an external operating handle 19 of any suitable character. This switch mechanism is claimed in my copending application #310,089, filed Oct. 3, 1928.

The switch is provided with suitable fuses such as 20 which are preferably enclosed laterally in a chamber formed by the insulating flange or receptacle 21. The cover is provided with an opening 22 which registers with the fuse chamber and this opening is provided with a slide or shutter 23 which is supported in guides 24 suitably secured to the cover. The shutter is provided with a suitable handle or finger piece 25 for manually operating the same.

The latch lever 26 is pivoted at 27 near its center and supported by a plate 28 secured to an inner wall of the box. The inner end of this lever is slotted at 29 to receive the switch operating crank 18. The outer end of the lever is provided with a shoulder or hook-like portion 30 adapted to stand in the path of movement of the projection 31 carried by the cover when the switch is closed and the cover is closed.

Preferably a spring 32 is connected to the lever 26 to hold it normally under tension so as to tend to move its outer end away from the cover. When the handle 19 is not restrained in the switch opening movement, this spring

32 causes the switch to open with a quick break movement.

When the parts are in the position shown in Fig. 3, that is, with the switch closed, the cover closed, and the shutter closed, it is impossible to open the shutter because the shoulder 30 stands directly in the path of movement of the upper end of the shutter projection 31. When the switch is open, however, the lever 26 is tilted by the crank 18 so as to retract the shoulder 30 from the path of movement of the shutter projection 31 and permit the shutter to be opened and thus permit access to the fuse chamber.

In the case the switch is closed while the cover is open and the shutter or slide is open, the subsequent closing movement of the cover, with the switch in this position, will cause the projection 31 to strike against the outer end of the lever 26 and tilt it and thus cause the slotted inner end 29 of the lever to co-act with the crank 18 and automatically open the switch. The spring 32 assists in this switch opening movement because of its tension on the lever and, provided the operating handle 19 is not restrained in the switch opening movement, this spring will cause a quick break movement of the switch blade 14 as soon as the blade has been freed from its comparatively tight contact with its co-operating stationary jaws 12 and 13.

For use in connection with certain types of switches, my present construction constitutes an important improvement over the Platt construction for a number of reasons. One is that it is better adapted to switches of the type in which the fuses are arranged above the switch blades.

It is also especially adapted to switch constructions in which the operating crank is positioned below or back of the base and it is applicable to such constructions regardless of the number of poles. The present construction is specially adapted to switches in which the line wires come into the bottom of the box and the load wires go out at the top or sides. The present construction also particularly adapts itself for convenient manufacturing and assembling. The latch itself in this preferred form is a perfectly flat bar or plate which may be stamped out of strip sheet metal.

By the present construction I have also made it possible to prevent leaving the shutter open when the cover is closed and the switch is closed, as the closing of the cover, under these conditions, automatically opens the switch and thus calls the attention of the operator to his failure to close the shutter as he should have done in order to house the fuses and thus properly protect the switch mechanism, the operator and the premises in which the construction is installed.

A feature of special importance is that no injury can be caused to any of the co-related

parts by the careless closing of the door when the interlocking parts are in relatively incorrect positions.

My present invention is not limited to use in connection with switches of the particular form shown herein but it is specially well adapted for use as shown. The lever is pivoted near its center and the latching point is positioned near the front of the box at one side of the lever pivot and the other end of the lever engages the switch crank at the other side of the pivot and near the bottom of the box thus making it possible to accomplish the desired objects by the use of a very cheap strip metal latching lever which requires no bending operations and is of such simple form and of such positive action that little, if any, fitting or adjusting is required in the assembling of the respective parts.

20 I claim:

1. A safety switch including a box having a cover with an opening near its center, a shutter for said opening, switch mechanism in the box having a base and having protecting fuse devices accessible through said opening, a switch operating crank pivoted in one end of said box beneath the switch base and a lever pivoted intermediate its ends alongside of said fuse devices and having its inner end slotted and operably connected with said crank and having a shoulder at its other end adapted to stand in the path of movement of said shutter to prevent opening said shutter when the cover is closed and the switch is closed, said switch mechanism being removable independently of said crank and lever.

2. A safety switch including a box having a cover with an opening, a slide for said opening, a switch operating crank and a lever having one end connected with said crank and having a shoulder at the other end adapted to stand in the path of movement of the slide to latch the slide closed when the switch is closed and said lever having a portion adapted to be engaged by said slide to move said lever and said switch crank to open the switch if the cover is closed while the switch is in closed circuit position and the shutter is partially opened.

3. A safety switch including a box having a cover with an opening, a shutter for said opening carried by said cover, a projection carried by said shutter, a switch operating crank pivoted in said box and a pivoted lever having one of its ends loosely connected with said crank and having a shoulder at its other end adapted to stand in the path of movement of said shutter to hold said shutter closed when the cover is closed and the switch is closed, said projection carried by the shutter being adapted to engage and move said lever to open said switch if the cover is closed while the switch is in closed position and the shutter is not fully closed.

4. A safety switch including a box having a cover with an opening, a shutter for closing said opening and carried by the cover, a projection carried by said shutter, a switch operating crank, and a lever pivotally mounted intermediate its ends and having one end connected with said crank and having a shoulder at the other end adapted to stand in the path of movement of the shutter to keep the shutter closed when the switch is closed, said shutter having a portion adapted to engage said lever and open the switch if the cover is closed when the shutter is open and the switch is in closed position.

5. A safety switch including a box having a cover hinged at one edge of the box and having an opening, a slide for said opening, a projection carried by said slide near the hinged edge of the cover, a switch operating crank pivoted near the bottom of the box and having an external handle near the opposite edge of the box and a lever pivotally mounted at approximately its center and having its inner end provided with an open slot detachably connected with said crank near the bottom of the box and having a hook-like shoulder at the other end adapted to stand in the path movement of the slide to keep the slide closed when the switch is closed.

6. A safety switch including a box having a cover with an opening, a shutter for closing said opening, a switch in said box, a switch operating crank pivoted in said box, a pivoted lever having one end operably connected with said crank and having a shoulder at the other end adapted to stand in the path of movement of said shutter to prevent opening said shutter when the switch is closed and a quick break spring for said switch connected to said lever.

7. A safety switch including a box having a cover with an opening, a slide for said opening, a projection carried by said slide, a switch in said box, a switch operating crank, a pivoted lever having one end connected with said crank and having a shoulder at the other end adapted to stand in the path of movement of the slide to prevent movement of the slide when the switch is closed and having a portion adapted to be engaged by the projection on said slide to move said lever and open the switch as the cover is closed when said shutter is open and said switch is in closed position and a quick break spring for said switch connected to said lever.

8. A safety switch including a box having a cover with an opening, a shutter for said opening carried by said cover, a projection carried by said shutter, a switch in said box, a switch operating crank pivotally mounted in said box, a lever having one of its ends loosely connected with said crank and having a shoulder near its other end adapted to

stand in the path of movement of said shutter to latch said shutter closed when the switch is closed, means carried by the cover and adapted to engage and move said lever and said switch crank under abnormal conditions and a spring connected to said lever for causing quick break movement of said switch.

9. A safety switch including a box having a cover with an opening, a shutter for said opening, a projection carried by said shutter, a switch in said box, a switch operating crank, a lever having one of its ends connected with said crank and having a shoulder at its other end adapted to stand in the path of movement of the shutter to keep the shutter closed when the switch is closed, said shutter having a portion adapted to engage said lever and move said switch operating crank to open the switch as the cover is closed when the switch is closed and the shutter is in a certain position and a quick break spring for said switch connected to, said lever.

20 10. A safety switch including a box having a cover with an opening, a slide for said opening, a projection carried by said slide, a switch operating crank, a lever having one end connected with said crank and having a shoulder at the other end adapted to stand in the path of movement of the slide to keep the slide closed when the switch is closed and having a portion adapted to be engaged to move said lever and open the switch as the cover is closed with the slide in the open position.

25 11. A safety switch including a box having a cover with an opening, a shutter for said opening, a projection carried by said shutter, a switch operating crank pivoted near the bottom of said box, and a lever pivoted near its center end having one end detachably connected with said crank and having a shoulder at the other end adapted to stand in the path of movement of said shutter to prevent opening said shutter when the switch is closed and a spring connected to said lever for assisting in opening the switch and tending to hold said lever out of the path 30 of movement of the shutter.

35 12. A safety switch including a box having a cover with an opening, a slide for said opening, a projection carried by said slide, a switch operating crank, a pivoted spring pressed lever having one end connected with said crank and having a shoulder at the other end adapted to stand in the path of movement of the slide to prevent movement of the 40 slide when the switch is closed and having a portion adapted to be engaged by the projection on said slide to move said lever and open the switch as the cover is closed when the switch is in closed circuit position and the 45 slide is in a certain position, said spring

tending to assist in the switch opening movement.

13. A safety switch including a box having a cover with an opening, a shutter for said opening carried by said cover, a projection carried by said shutter, a switch operating crank pivoted in said box and a lever having its inner end detachably connected with said crank and having a shoulder near its outer end adapted to stand in the path of movement of said shutter to hold said shutter closed when the cover is closed and the switch is closed, said projection carried by the shutter being adapted to engage and cause a switch operating movement of said lever if the cover is closed when the switch is closed and the shutter is not fully closed, and a spring connected to said lever for assisting in the opening of the switch.

14. A safety switch including a box having a cover with an opening, a shutter for said opening, a switch mounted in said box having protecting fuse devices exposed through said opening when said shutter is open, a switch operating crank and a lever having one end detachably connected with said crank and having a shoulder at its other end adapted to stand in the path of movement of the shutter to keep the shutter closed when the cover is closed and the switch is closed, said shutter having a portion adapted to engage said lever and open the switch if the cover is closed when the switch is closed and the fuse devices are exposed, and a spring connected to said lever to assist in opening the switch.

HERMAN J. HAMMERLY.
